LADY'S HANDBAG, OR SIMILAR ARTICLE

Murray Resnick, Miami Beach, Fla., assignor to
J. R. Handbags, Inc., Miami, Fla.

Filed Nov. 10, 1971, Ser. No. 197,591

Term of patent 14 years

Int. Cl. D3—01

U.S. Cl. D87—3 F

FIG. 1 is a side perspective view of a lady's handbag or similar article showing my new design, the side opposite being substantially identical thereto;

FIG. 2 is a side elevational view thereof, with the cover removed; and

FIG. 3 is an end elevational view thereof, the handle being broken away for convenience of illustration.

I claim:

The ornamental design for a lady's handbag, or similar article, as shown and described.
